(57) **CLAIM**

The ornamental design for a light, as shown and described.

DESCRIPTION

FIG. 1 is a perspective view of a light;

FIG. 2 is a side view thereof, an opposing side, a front and a rear being identical;

FIG. 3 is a top view thereof; and,

FIG. 4 is a bottom view thereof.

The broken lines shown in the drawings are included for purposes of illustrating portions of the light and form no part of the claimed design.
